UNITED STATES PATENT OFFICE.

FLOYD A. HIGERD, OF BELLEVUE, PENNSYLVANIA, AND GEORGE BECKER, OF SILVER CREEK, NEW YORK, ASSIGNEES TO H. J. HEINZ COMPANY, OF PITTSBURGH, PENNSYLVANIA, A CORPORATION OF PENNSYLVANIA.

MEANS FOR SHIPPING FRUIT, ETC.

Application filed April 17, 1922. Serial No. 553,655.

To all whom it may concern:

Be it known that we, FLOYD A. HIGERD, residing at Bellevue, in the county of Allegheny and State of Pennsylvania, and 5 GEORGE BECKER, residing at Silver Creek, in the county of Chautauqua and State of New York, citizens of the United States, have invented or discovered certain new and useful 10 Improvements in Means for Shipping Fruit, Etc., of which improvements the following is a specification.

Our invention relates to improvements in means for shipping fruit, and is, as present- 15 ly will be apparent, applicable to the trans- portation of all sorts of delicate and easily crushed articles. We have developed it in the shipment of fresh tomatoes, and in that particular application we shall describe it; 20 its wider applicability will be manifest. The objects of invention are, primarily, the ability to make large shipments in relatively small space. Incidentally, we have de- 25 veloped a container which is convenient, durable, economical, and requires but little space in shipment in quantity when empty and in storage.

In the accompanying drawings Figures I, II, and III are views in plan from above, in side elevation, and in transverse vertical 30 section (on the plane indicated by the line III—III, Figure II) of a single container in which and in the use of which our invention is found. Figures IV and V are views to smaller scale, showing, in plan from above 35 and in side elevation, a collocation of containers, such as that of Figures I—III, in which collocation the invention is fully realized.

In the shipment of such soft and perish- 40 able articles as tomatoes the permissible size of a unit container is manifestly limited by the nature of the article: the container may not be so large that tomatoes placed in the bottom of the container will be crushed by 45 the superposed mass of fruit. In fruit-growing regions, when the crop is being gathered and shipped, there is great demand for freight cars, and that unit container is best which, other things being equal, will 50 make possible the filling of a freight car with the greatest possible load of tomatoes, the load being safe against damage in consequence of great weight, and being so conditioned, in the matter of air circulation, as

to preserve the fruit in good condition dur- 55 ing transportation. Our invention is found in a container which is adapted to meet these conditions in best manner.

The container of our invention is a basket, 60 rectangular in plan, flat-bottomed, somewhat longer than wide, somewhat wider than deep; its sides extend each in a single plane, and they slope and flare, from the bottom upwardly. The actual dimensions of the basket which we have successfully worked 65 out for tomatoes are these: at the top, 13 $\frac{1}{2}$ by 19 inches; at the bottom 10 by 14 $\frac{1}{2}$ inches; depth, 9 inches. These dimensions we be- 70 lieve to be best, considering the conditions of service indicated above, and considering also ease and convenience of handling in loading and unloading. The rectangular shape in plan and the sloping side walls are, 75 as presently will more fully appear, impor- 80 tant features.

The material of which the basket is made is not a matter of controlling importance; but thin splint-wood, widely used for such purposes is best. It is light and porous and sufficiently pliant and resilient under weight 85 and stress. The basket as we prefer to make it consists of a bottom board 1 (which ordi- 90 narily will be heavier than the thin-splint wood alluded to) sides 2, which are made of such thin-splint wood, and strengthening and securing bands. An outer band 3 over- 95 lies the side splints at the bottom, and through it the side splints may be nailed to the bottom board. Inner and outer bands 4 and 5 bind between them the upper edges 100 of the side splints and constitute the rim of the basket. These bands 3, 4, and 5 are preferably formed of wood, serving after the manner of barrel hoops. Strengthening 105 and stiffening angle irons 6, 7, and 8 may be provided at the corners, angle 6 below, secured through band 3 and splint-wood sides to bottom board 1, and angles 7 and 8 above, the one within the other without and riveted together, through bands 4 and 5 and through the splint-wood wall.

The strips of splint-wood which consti- 110 tute the side walls of the basket will ordi- narily be spaced apart, at the edges some- what as indicated at *a*. These spaces may at the ends be widened, as indicated at *b*, to af- 115 ford hand holes, beneath the binding bands.

Along opposite margins above (preferably

the longer margins, if the basket be longer than wide) the splints extend interruptedly above the binding bands 4 and 5, to form the "castellated" edge, best shown in Fig. II: 5 at a plurality of opposite points *c*, *c*, and *d*, *d*, the edges of the splints, which elsewhere extend a short distance above the binding bands, are cut away, flush with the bands. Thus opposite notches are formed 10 in the rim of the basket, and the edges of bands 4 and 5 form the bottoms of these notches.

Turning to Figures IV and V, the purpose 15 of these notches will be manifest. Here is shown an assembly of identical baskets, stacked together after the manner employed when a freight car or other vehicle is loaded with baskets full of fresh fruit. The frame of a freight car is indicated at 10; the 20 floor at 11. There is a succession of vertically superposed tiers. The baskets of each tier are set close, rim to rim and corner to corner, so that the open tops of the baskets of any one tier completely occupy the plane 25 in which the rims extend. Billets 9 are laid across, above each basket of each inferior tier, the ends of the billets resting in the aligned notches *c* and *d* of adjacent baskets. And on these billets so laid the baskets of 30 the superposed tier directly rest. The up-standing splints which delimit the notches on either side insure proper placement of the billets; the notches are sufficiently wide to receive the ends of two billets laid side by 35 side; the upstanding edges of the splints do not rise so high as the thickness of the billets; the billets are conveniently made but little longer than the width of a single basket.

40 In filling a freight car with baskets of our invention it may and commonly will be preferable to use longer billets extending throughout the width of the car and each extending above several baskets, and this departure from the minute showing of the drawings is an obvious one.

Comparing Figures IV and V, it will be 45 remarked that, in consequence of the continuous contact of edges of adjacent baskets, and of the opposite inclination of side walls of adjacent baskets upwardly to a line of contact, the assembled baskets and billets form a relatively rigid well-braced structure. At the same time, the spaces in the 50 assembly, consequent upon the inclination of the side walls of the baskets, taken together with the ventilating spaces in the structure of the side walls, and the absence of any close fitting closures upon the individual baskets insures the air circulation requisite to keep such soft and perishable fruit as tomatoes, particularly when so closely packed, in good condition.

60 Hitherto, so far as we are aware, no other container for tomatoes, excepting only par-

allel-sided, square-cornered crates, can be packed in freight cars to a height of more than three or four tiers. Such crates, if they are to keep their position under the strains and jars of haulage must be packed in close 70 contact, and when so packed ventilation is insufficient, and the fruit will rapidly spoil. Furthermore, a vertical-walled container is not well adapted for carrying soft fruit, for the underlying fruit sustains the full weight 75 of the superposed mass. The side walls afford no aid. Consequently vertical-walled crates are used chiefly for such firm fruit as melons, apples, and oranges; if used for 80 softer fruits, they must be made very shallow. The only containers, heretofore available which when assembled afford the requisite ventilation are the ordinary round "peach baskets," and they are such in structure that when assembled in tiers, the whole 85 assembly is weak; the underlying baskets cannot sustain great superposed loads without deformation and consequent crushing of the fruit. As a matter of fact peach baskets filled with tomatoes may not safely be 90 stacked in freight cars to a height of more than four tiers. Our baskets may be stacked to a height of eight or more tiers, practically filling the freight car. With our invention a freight car may carry twice as many tomatoes safely as when peach baskets are the only available containers. Furthermore, in 95 stacking peach baskets it is the practice to use small metal clamps, binding basket to basket, rim to rim. These often loosen and 100 lose themselves in the fruit, and become subsequently a cause of injury to machinery.

Our empty baskets may be nested, as parallel-sided crates may not, and being nested may be transported and stored with greatest 105 economy of space. They are lighter than crates; less material is required for a given capacity. An ordinary peach basket has a life of two years; our basket will endure far longer service,—as much, we have reason to believe, as eight or ten seasons. Its initially greater cost than a peach basket finds full compensation (and more) in durability.

110 Considering the loaded freight car, the contained tomatoes are segregated into pockets of maximum size, all things considered, disposed in best position, each free of the stresses and strains incident to the bringing together of many such units in superposed tiers.

115 We claim as our invention:

1. A container for fragile articles having side walls formed of strips of sheet material, bound at the rim by a transversely extending band, the strips of sheet material extending interruptedly beyond and above the band and forming with the band a notched rim.
2. An assembly of two containers and a plurality of billets, the nether container having side walls formed of strips of sheet ma-

terial, bound at the rim by a transversely extending band, the strips of sheet material extending interruptedly beyond and above the band and forming with the band a plurality of pairs of opposite notches in the rim, the said billets resting each in a pair of opposite notches and the upper container resting on said billets.

3. An assembly of containers for fragile articles, each container having inclined side walls, a polygonal rim, and notched upper edges, the containers being assembled in superposed tiers, the containers of each tier standing rim to rim, billets laid in the notches of the rims of an inferior tier, and the containers of the superior tier resting on the billets of the interior tier.

4. An assembly of containers for fragile articles, each container being rectangular in plan and having inclined side walls and having aligned notches in opposite rims, the containers being assembled in tiers, the con-

tainers of each tier standing edge to edge and corner to corner with adjacent containers, and with rim notches aligned, billets laid in the notches and overlying each container of an inferior tier, and the containers of each superior tier resting directly on the billets borne by the containers of the next inferior tier, the whole assembly being, in virtue of such features of shape and arrangement, braced to resist crushing strain, substantially as described.

In testimony whereof we have hereunto set our hands.

FLOYD A. HIGERD.
GEORGE BECKER.
